ROLLER COTTON GIN

Frank E. Deems, Birmingham, Ala., assignor to Continental Gin Company, Birmingham, Ala., a corporation of Alabama

Filed May 22, 1962, Ser. No. 196,644

4 Claims. (Cl. 19—50)

This invention relates to a cotton gin and, in particular, a roller cotton gin characterized in operating with a high degree of efficiency and having high capacity.

Roller cotton gins are well known and one well known type is illustrated in the Williams, Jr., et al. Patent 2,929,111. This type of roller cotton gin delivers seed cotton to the periphery of a ginning roller and bars pass over the roller and co-operate with the roller and a stationary knife blade to effect separation of the seeds from the lint cotton, whereupon, the seeds and the lint cotton are separately collected and the ginning operation is thereby accomplished.

Roller cotton gins according to the Williams, Jr., et al. patent, however, have a number of drawbacks that it is proposed to overcome by the structure of the present invention. In particular, the chains carrying the bars are guided over sprockets in prior art roller gins and this does not provide the best path of travel for the bars to operate efficient ginning of the seed cotton while, at the same time, protecting the ginning roller from undue wear due to abrasion by the bars.

Still further, sprockets, when chains are run thereover at high speeds, tend to cause vibration on the chains and high speed operation of roller cotton gins of this nature is, therefore, difficult and the vibration set up in the ginning structure detracts from the efficiency of operation of the cotton gin. For example, such vibration could cause the knives or bars to lose their grip on the fibers at the very time when such a grip is required to effect proper ginning of the cotton.

Still further, no sprocket support for the roller chains carrying the knives or bars can give exactly the best possible path of travel to the bars at the time that they pass over the end of the stationary knife provided adjacent the periphery of the ginning roller and which knife is effective for causing the actual separation of the seed from the lint cotton.

With the foregoing in mind, a primary object of the present invention is to provide a roller cotton gin of greatly improved operating characteristics.

A still further object of the present invention is to provide a roller cotton gin in which knives or bars are carried by chains adjacent the periphery of the ginning roller and wherein the path of travel of the said knives or bars is not dependent on the sprockets for the support chains which carry the knives or bars.

A still further object of this invention is the provision of a roller cotton gin in which inefficient operation on account of vibration is eliminated by eliminating the said vibration.

Still a further object of the present invention is the provision of a roller gin structure in which the chains that carry the knives or bars that move across the surface of the ginning roller are supported and guided externally of the lower part of the ginning structure thereby leaving this entire portion of the structure more accessible for work on the ginning roller and for exposing the sections of the gin which receive the unginned cotton and which receive the ginned cotton lint.

These and other objects and advantages of this invention will become more apparent upon reference to the following specification, taken in connection with the accompanying drawings in which:

FIGURE 1 is a somewhat diagrammatic vertical sec-

2

tional view taken through a roller cotton gin constructed according to my invention;

FIGURE 2 is a sectional view indicated by line 2—2 on FIGURE 1 showing the ginning roller and the manner in which the bars or knives are supported relative to the ginning roller;

FIGURE 3 is a sectional view indicated by line 3—3 on FIGURE 2 showing the cam means which guide the bar or knife supporting chains during the travel thereof over the ginning roller and also showing the adjustable supports for the cam means;

FIGURE 4 is a somewhat diagrammatic view showing the ginning action as it occurs in a roller cotton gin according to the present invention; and

FIGURE 5 is a somewhat modified arrangement with the knife or bar mounted in a somewhat different location relative to the rollers of the supporting chains.

Referring to the drawings somewhat more in detail, the various parts of a roller cotton gin according to my invention are somewhat diagrammatically illustrated in FIGURES 1 and 2 wherein it will be seen that the structure comprises a casing 10 and mounted within the casing is a rotatable ginning roller 12. Mounted within the casing for movement over the surface of ginning roller 12 are a plurality of spaced carrier chains 14.

These chains are supported on sprockets 16, at least one of which is driven so that the chains move in the path indicated by the arrows 18. Simultaneously with the movement of the chains, the ginning roller rotates in the direction of the arrow 20 thereon and overspeeds the chains by from about twenty-five percent to about two hundred fifty percent.

Extending laterally of the ginning roller are bars or knives 22 which are attached to the chains to be moved therewith.

The upper portion of the ginning roller, which is the portion over which the bars or knives 22 move in proximity to the surface of the ginning roller, is exposed between a shield member 24 at one side and a stationary ginning knife 26 at the other side. This exposed surface of the ginning roller is the region in which the lint cotton is separated from the seeds as the seed cotton passes through the roller cotton gin of the present invention.

The seed cotton is supplied to the upper portion of the ginning roller by way of a feed passage 28 which extends upwardly from the ginning roller and at the top of which is an in-fed conveyor means 30 which might be, for example, a screw conveyor.

The seed cotton is delivered in a transverse direction by the conveyor in this manner because, as contrasted to roller cotton gins of the prior art, the chain means 14 of the present invention take their return movement above the ginning roller rather than beneath the ginning roller. This has the advantage of exposing the entire roller portion of the structure for the instrumentalities necessary for receiving the gin cotton and for discharging cotton seeds and for removing partially ginned cotton and returning it to the gin for being again passed therethrough.

The seed cotton delivered by in-feed conveyor means 30 is delivered to a pair of feed rollers 32 which are adapted for being driven at a predetermined speed by an adjustable speed drive generally indicated at 34. This adjustable speed drive permits the feeding of cotton downwardly to the ginning roller at the desired rate of speed.

Beneath the speed rollers 32 is another speed roller 36 that accomplishes the final movement of the seed cotton downwardly to the ginning roller.

Associated with the chain means immediately after it leaves the ginning roller is a rotating wiper device 38 that is operable for stripping lint and cotton seed and

partially ginned cotton from the bars or knives that might adhere thereto and for delivering this material down an incline plate 40 to a reclainer saw 42.

Positioned immediately above reclainer saw 42 and running fairly closely adjacent the bars or knives 22 and also closely adjacent wiper 38 is a second reclainer saw 44 which insures that all of the partially ginned cotton and the like will be delivered to saw 42.

In a manner known in the art of cleaning cotton, saw 42 whips the material delivered thereto over the bars 46 and, in this manner, extracts at least some of the seeds therefrom and which seeds drop downwardly in the casing, some thereof passing through the inclined grill 48, and those thereof still containing any substantial amount of lint, being delivered to another reclainer saw 50.

Reclainer saw 50 whips the material delivered thereto over another set of bars 52 extracting still more of the seed therefrom. The unginned seed cotton, or cotton fibers that still remain on the saws 42 and 50 are removed therefrom by doffing brush 54 and delivered into a chute 56. This material, which can be designated reclaimed seed cotton or lint, is conducted via conveyor means generally indicated at 58 back to the incoming conveyor means 30 and again passed through the gin.

The seeds that pass through the grill 48 and those that are passed through bar 52 drop into a discharge chute 60 which may have a discharge conveyor means 62 therein for conveying them away from the ginning structure.

Returning now to the ginning roller 12, the fibers that are carried by this roller beneath knife 26 drop into the ginned cotton hopper 64, or are removed from the ginning roller by doffing roller 66, or by an air blast or the like, so that all of the clean cotton fibers from the ginning roller are delivered to hopper or chute 64 from which they pass to a further processing station.

The bars or knives 22 carried by the chains are cleaned after passing the wiper 38 as by being subjected to suction from a nozzle 68 that is connected to a suction flue 70. This picks up loose locks of seed cotton and loose fibers and this material can be returned to the in-feed conveyor means 30 in any suitable manner.

The present invention is further concerned with the guiding of the chains 14 and the knives carried thereby when they are passing in the immediate vicinity of the ginning roller. This is accomplished by supporting the chains by cams during this portion of their travel rather than sprockets so that the movement of the chains and knives can be guided along the exact path desired and also so as to eliminate vibration of the chains and knives which would occur as a natural consequence of passing the chains around small sprockets as has been done heretofore.

Still further, by utilizing cams to guide the chains, the chains can be caused to carry the knives along in proximity to the surface of the ginning roller for a substantially longer distance than has heretofore been possible when supporting the chains on sprockets. This increases the length of time that the locks of cotton are subjected to the ginning action which takes place between the ginning roller and each bar or knife and thus substantially increases the capacity of the gin and also increases the efficiency of the ginning action thereof.

The cam arrangements for supporting the chains will best be seen in FIGURES 2 and 3. In these views, it will be seen that there is located at each of the ginning roller 12 and secured to the walls 72 of the casing 10, the cams 74 which engage the outermost chains 14. These cams are contoured to support and guide chains 14 so as to hold the knives or bars 22 carried thereby in exactly the proper relation to the adjacent surface of the ginning roller throughout the time that the bars or knives are passing over the surface of the ginning roller.

The cams 74 are preferably adjustably mounted on

the respective casing walls, as by having one end supported by eccentric pin means 76 and having bolt means 78 at the other end passing through a slot 80 in the wall 72. An adjustable abutment screw 82 is arranged adjacent each cam 74 at the end opposite eccentric pin 76 and, in this manner, the exact positioning of the cams can be adjusted.

It will be understood that the eccentric pin 76 could be replaced by another adjustable means, the essential thing being that the cam is adjustably supported so that it can be positioned very exactly relative to the ginning roller.

Cam 74 guides the chains and the bars or knives carried thereby while the bars or knives pass about the ginning roller, but it is also important to guide the chains and bars as they leave the ginning roller and pass over the knife 26. This is accomplished by still another cam means, one of which is indicated at 84 in FIGURE 1. This is a circular cam about which the chains pass as they leave the ginning roller.

This cam, of course, can be adjustably supported in any desired manner.

Another such cam arrangement is indicated at 86 in FIGURE 3. This cam arrangement is adjustably supported on the casing as by bolts 88 with there being a plurality of adjusting screws 90 distributed about the cam for adjusting the precise position thereof.

The cam means 74, as mentioned above, is important for guiding the chains and the bars carried thereby during the time that the bars are moving in proximity to the surface of the ginning roller, while the cam means 84 or 86 determine the path taken by the chains and the bars or knives as they leave the surface of the roller and pass over the stationary knife 26.

The movement of the bars or knives 22 during this period is illustrated in FIGURE 4 wherein it will be seen that fibers are being drawn under the stationary knife 26 by the ginning roller, while the seeds are caused to pass over the stationary knife by the bars or knives 22.

FIGURE 4 shows the knives connected to the chains intermediate the individual rollers 92 of the chains and the knives are cradled thereby causing the leading and trailing edges of the knives 22 to follow essentially the same path past stationary knife 26, whereas, FIGURE 5

shows an arrangement wherein the knives 22 are connected to the links 94 in the region of the leading edge of the rollers 92. The FIGURE 5 arrangement provides a somewhat different path for the trailing edges of the knives 22 in that the trailing edges follow the dashed line of FIGURE 5 which path is closer to cam 84 or cam 86, which cams determine the path taken by the chains and moving knives as they leave the surface of the roller and pass over stationary knife 26. It should be noted that in the FIGURE 5 arrangement, the knives 22 do not

begin to rotate clockwise until the trailing edges are past the seeds retained on stationary knife 26. In FIGURE 5, the trailing edge is closer to the center of cam 84 (better seen in FIGURE 1) than the leading edge. Since there is little movement of the knives 22 on the cam 84, the knives 22 will retain this position relative to the stationary knife 26 until the trailing edge is past the knife 26 as shown by the dotted line of FIGURE 5. This permits the trailing edges to pass over the seeds and allow the leading edges of the next following knives to engage the said seeds and push them over the top of the stationary knife 26.

Inasmuch as that, even with the knives 22 supported so as to move in close proximity to the ginning roller 12, some wear of the ginning roller will take place and, in order to compensate for this, the shaft 96 of the roller is supported in bearings 98 that are adjustable toward and away from knife 26 in the direction of the arrow 100 in FIGURE 1 so that the ginning roller can be maintained in proper relation to the stationary knife.

A gin according to the present invention, to give a

specific example, that is not intended to be in any way limiting, might employ a ginning roller of from twelve to fifteen inches in diameter rotating at a surface speed of from about two thousand to eight thousand inches per minute. The speed of the moving knives which is always less than the surface speed of the ginning roller, might range from about one thousand to four thousand inches per minute.

The knives may be made of square stock from one-half to one inch or so on a side and are spaced apart from about one-half to four inches along the supporting chains therefor.

A gin according to the present invention, over prolonged periods, is capable of producing clean lint at a rate of up to four times or more the capacity of conventional roller gins.

It will be understood that the ginning roller is possessed of a surface characterized in that the fibers of cotton will cling thereto so that as the ginning roller rotates, the fibers are dragged along the surface of the ginning roller. On account of the arrangement of the present invention whereby the moving knives are held closely adjacent the surface of the ginning roller for a substantial distance, in fact, for substantially the entire distance of the region where the seed cotton is delivered to the ginning roller and the point where the stationary knife is located, it will be apparent that there will be a prolonged ginning action between the ginning roller and the moving knives that will greatly increase the efficiency of operation of the arrangement and in addition will protect the surface of the ginning roller because the moving knife means will be held in spaced relation thereto.

It will be understood that the stationary knife means bears on the surface of the ginning roller and under no operative conditions does it ever become spaced from the roller by more than the lateral dimension of a cotton seed so that while fibers can be drawn under the stationary knife by the ginning roller, the seeds will be prevented from passing beneath the stationary knife and will, instead, be forced over the stationary knife by the moving knife means and, in this manner, be separated from the cotton fibers.

It will be understood that this invention is susceptible to modification in order to adapt it to different usages and conditions, and, accordingly, it is desired to comprehend such modifications within this invention as may fall within the scope of the appended claims.

I claim:

1. In a cotton gin; a ginning roller rotatable on a horizontal axis, means for feeding seed cotton to the surface of said ginning roller at a predetermined circumferential point thereof, a stationary knife adjacent said ginning roller slightly spaced from the surface thereof and located circumferentially about the roller from the said feed means in the direction of rotation of the roller, a plurality of moving knives having leading and trailing edges extending in a direction parallel to the axis of the ginning roller and arranged in parallel spaced relation, support chains connected with said moving knives, sprockets supporting said chains and providing one reach of the chain extending adjacent the periphery of the ginning roller in the region between said feed means and said stationary knife, and adjustable cam means having arcuate sliding surfaces engaging said support chains in the said reach thereof that is adjacent the ginning roller and guiding said chain means so that the knives carried thereby follow a fixed path between said feed means and said stationary knife that is parallel to and slightly spaced from the surface of said ginning roller for pre-ginning the seed cotton and for eliminating whip in said support chains, thereby providing a pre-ginning of the seed cotton prior to reaching said stationary knife, said support chains comprising spaced rollers and links extending therebetween, and said moving knives being attached

to links of said chains in the center thereof in order that the said leading and trailing edges of said knives follow approximately the same path past said stationary knife.

2. In a cotton gin; a ginning roller rotatable on a horizontal axis, means for feeding seed cotton to the surface of said ginning roller at a predetermined circumferential point thereof, a stationary knife adjacent said ginning roller slightly spaced from the surface thereof and located circumferentially about the roller from the said feed means in the direction of rotation of the roller, a plurality of moving knives having leading and trailing edges extending in a direction parallel to the axis of the ginning roller and arranged in parallel spaced relation, support chains connected with said moving knives, sprockets supporting said chains and providing one reach of the chain extending adjacent the periphery of the ginning roller in the region between said feed means and said stationary knife, and adjustable cam means having arcuate sliding surfaces engaging said support chains in the said reach thereof that is adjacent the ginning roller and guiding said chain means so that the knives carried thereby follow an arcuate path between said feed means and said stationary knife that is parallel to and slightly spaced from the surface of said ginning roller for pre-ginning the seed cotton and for eliminating whip in said support chains, thereby providing a pre-ginning of the seed cotton prior to reaching said stationary knife, said support chains comprising spaced rollers and links extending therebetween, and said moving knives being connected with links of said chains at the leading ends of said links for imparting a predetermined relationship between the path taken by the leading edge of each moving knife and the trailing edge thereof.

3. A method of ginning seed cotton which comprises; feeding the seed cotton to the periphery of a rotating ginning roller, moving the seed cotton by the ginning roller to a stationary knife spaced circumferentially about the ginning roller from the point of feeding cotton thereto and in the direction of rotation of the ginning roller, drawing the fibers of the cotton beneath the stationary knife by the ginning roller while the stationary knife prevents movement of the seeds with the said fibers, and conveying moving knives in spaced relation and arranged parallel to the axis of rotation of the ginning roller thereover between the point of feeding the seed cotton to the ginning roller and the stationary knife, supporting and guiding said moving knives so that they move parallel to the surface of the ginning roller and in slightly spaced relation thereto whereby a prolonged ginning action is had between each moving knife and the ginning roller before reaching said stationary knife, and moving the said moving knives in the same direction as the surface of the ginning roller but at a lower speed.

4. In a cotton gin; a ginning roller rotatable on a horizontal axis, means for feeding seed cotton to the surface of said ginning roller at a predetermined circumferential point thereof, a stationary knife adjacent said ginning roller adjacent to the surface thereof and located circumferentially about the roller from the said feed means in the direction of rotation of the roller, a plurality of moving knives extending in a direction parallel to the axis of the ginning roller and arranged in parallel spaced relation, support chains forming a closed path connected with said moving knives, sprockets supporting said chains and providing one reach of the chain extending adjacent the periphery of the ginning roller in the region between said feed means and said stationary knife, and first cam means having arcuate sliding surfaces supportingly engaging said support chains in the said reach thereof that is adjacent the ginning roller and guiding said chain means so that the knives carried thereby follow a fixed path between said feed means and past said stationary knife that is parallel to and slightly spaced from the surface of said ginning roller for pre-ginning said seed cotton and for eliminating whip in said support

chains, said ginning roller being adjustable toward and away from said stationary knife, there being second cam means having arcuate sliding surfaces supportingly engaging said support chains after the said chains have passed said stationary knife for guiding the support chains and the said moving knives carried thereby as the moving knives leave the region of the ginning roller and pass over said stationary knife, said first and second cam means being adjustably supported for adjusting the exact location of the path taken by said moving knives relative

to the surface of the ginning roller and relative to said stationary knife, and said support means being adapted to travel over said first cam means and under said second cam means.
